Henry Levin, Long Island City, N. Y.

Application September 25, 1945, Serial No. 122,332

Term of patent 3½ years

(Cl. D44—4)

To all whom it may concern:

Be it known that I, Henry Levin, a citizen of the United States of America, residing in Long Island City, county of Queens, and State of New York, have invented a new, original, and ornamental Design for Ice Tongs or Similar Article, of which the following is a specification, reference being had to the accompanying drawing, forming part thereof, wherein,

I claim:

The ornamental design for ice tongs or similar article, substantially as shown.

HENRY LEVIN.
